The ornamental design for a multiple antennas assembly, as shown and described.

DESCRIPTION

FIG. 1 is a front elevation view of a multiple antennas assembly;

FIG. 2 is a side elevation view thereof;

FIG. 3 is a second side elevation view thereof;

FIG. 4 is a bottom plan view thereof;

FIG. 5 is a top plan view thereof;

FIG. 6 is a top perspective view thereof;

FIG. 7 is a front elevation view of a multiple antennas assembly illustrated within a box in broken lines;

FIG. 8 is a side elevation view thereof;

FIG. 9 is a second side elevation view thereof;

FIG. 10 is a bottom plan view thereof;

FIG. 11 is a top plan view thereof; and,

FIG. 12 is a top perspective view thereof.

The broken lines are for illustration purposes only and form no part of the claimed invention.
